UNITED STATES PATENT OFFICE

JOHN F. O'CONNOR, OF CHICAGO, ILLINOIS, ASSIGNOR, BY MESNE ASSIGNMENTS, TO
W. H. MINER, INC., A CORPORATION OF DELAWARE

ANTIFRICTION ROLLER SIDE BEARING

Application filed April 3, 1924. Serial No. 703,901.

This invention relates to improvements in anti-friction roller side bearings.

One object of the invention is to provide a simple, practical and relatively inexpensive roller bearing especially adapted for use as a railway car side bearing and wherein the parts are so arranged that the anti-friction element proper is automatically returned to its normal central position when free from load.

Another object of the invention is to provide a device of the character described that is self-contained, all parts of which are maintained in permanently assembled relation and which is adapted to be applied as a unit to the bolster of a railway car.

Another object of my invention is to provide, in a bearing of the kind described, an anti-friction roller acting in cooperation with a pair of side members, said parts being so arranged that the roller will transmit the full load for a predetermined part of its travel from central position, said side members displacing the roller so that the load is thereafter transmitted to the roller and side members in series, the continued travel of said roller and side members terminating at the extreme position of the side members, in which position the roller is free to rotate under continued travel of the cooperating bolster.

Other objects and advantages of my invention will more clearly appear from the description and claims hereinafter following.

In the drawing forming a part of this specification, Figure 1 is a vertical sectional view taken through the ends of the body and truck bolsters of a railway car, showing my improvements in connection therewith. And Figure 2 is a vertical sectional view corresponding substantially to the line 2-2 of Figure 1.

In said drawing, 10 denotes the upper side of a truck bolster and 11 the under side of the corresponding opposed body bolster. The improved side bearing is shown as applied to the body bolster and comprises broadly, a base casting, retaining member or housing A; an anti-friction element proper B; rockers or side members C-C at the ends

of said anti-friction element; and springs 27-27.

The housing A is more or less box-like in form, having curved end walls 12 and vertical side walls 13, the lower ends of said side walls being flanged inwardly toward one another as indicated at 14 to provide an opening 15 therebetween, and the upper ends of said side walls being flanged inwardly toward one another as indicated at 16. Openings are provided centrally of the housing through said top flanges 16 as indicated at 17 for a purpose to be hereinafter described. A bearing plate 18 is adapted to be interposed between the housing and the body bolster to receive the thrust transmitted to the cooperating truck bolster. Lugs 19 are provided on the housing, said lugs extending laterally therefrom and adapted to receive rivets 20 therethrough, whereby the housing may be secured to the bearing plate 18. The bearing plate is in turn secured to the body bolster by rivets 21 or the like. Extending inwardly from the opposite end walls of the housing are webs 22, said webs forming abutments or stops in a manner to be hereinafter described.

The anti-friction element B is in the form of an anti-friction roller adapted to roll back and forth on the bearing plate 18 and project through the opening 15 between the flanges 14 of the housing, so that when the load is applied, said roller will engage between the bearing plate 18 and the truck bolster 10, and transmit the load therebetween. Positioned axially through the roller is a pin having its ends 23 projecting beyond the ends of the roller.

The side members or rockers C are arranged one at each end of the roller, said rockers having hubs 24 provided with bores 123 therethrough whereby the rockers may be pivotally mounted upon the projecting ends 23 of the pin. The upper ends of said rockers are made arcuate as at 25 and have a radius greater than that of said roller and eccentric thereto, so that when the rockers are mounted upon the pin projections and are in their normal central position, the centers of said arcuate edges are spaced a slight distance from the bearing plate 18, while the

roller B is in engagement therewith. Lugs or projections 26 extend laterally from the upper ends of said rockers as shown.

In order to maintain the parts in their normal central position, there is a resilient member or spring 27 arranged between each rocker and the outer wall 13 of the housing, each spring having its ends curved and engaging the curved end walls and the bottom flange of the housing, said spring being provided with a downwardly extending depression 28 at its center, this depressed portion 28 being adapted to pivotally receive the projections 26 of the rockers to support the rockers and roller in position.

In assembling the parts, the roller and rockers are first inter-connected by means of the pin and are then inserted into the housings, the projections 26 passing through the opening 17 of the top flanges 16, the springs 27 being already in place within the housing so that the rocker projections 26 will seat in the spring depressions.

The operation of the device is as follows, assuming that the roller is moved to the right toward its dotted line position shown in Figure 1. During the first portion of travel, the roller rolls along the bearing plate for a predetermined distance, directly transmitting the full load between the bearing plate and truck bolster until those portions of the arcuate edges of the rockers that project beyond the periphery of the roller engage said bearing plate, whereupon the load is transmitted thru the roller and rockers in series, after which the rockers, working against the spring pressure move the roller away from the bearing plate a slight distance, said rockers rocking until their hubs 24 abut against the stops 22 of the housing. After the roller is lifted away from the bearing plate it may revolve on its journals about a fixed axis to thus permit unlimited travel.

It will be noted that the bearing plate 18 is of sufficient width so that both the rockers and the roller may bear thereagainst. As the rockers are rocked toward their extreme positions, the springs are flexed, so that when the load is released, the springs will return the rockers and roller to their normal central position.

It will be evident that by the construction hereinbefore described, I have produced a side bearing which is self-contained, and which may be applied to the bolster as a unit, said parts being held in permanently assembled relation so that the parts thereof are not lost before shipment or application to the railway car.

I have herein shown and described what I now consider the preferred manner of carrying out my invention but the same is merely illustrative and I contemplate all changes and modifications that come within the scope of the claims appended hereto.

I claim:

1. In an anti-friction bearing, the combination with a housing adapted to be secured to a body bolster and having an interior bearing surface; of an anti-friction roller; a rocker connected to each end of said roller and having an arcuate bearing surface eccentric to the bearing surface of said roller and projecting therebeyond at the ends of the rockers; and means for pivotally suspending said rockers from a point above their connections to said roller, said rockers transmitting the load between said bearing surface of the housing and the truck bolster after the rockers have been rocked a predetermined amount; and means for centering said parts after the load has been removed.

2. In an anti-friction bearing, the combination with a housing adapted to be secured to a body bolster and having an interior bearing surface; of an anti-friction roller; a rocker connected to the axis of said roller at each end thereof, each rocker having an arcuate bearing surface eccentric to the bearing surface of said roller and projecting therebeyond at the ends of said rockers; and resilient means for pivotally supporting said rockers from a point above their connections to said roller, said roller initially transmitting the load between said bearing surface of the housing and the truck bolster and said rockers transmitting the load to said bearing surface after they have been rocked a predetermined amount by said roller.

3. In an anti-friction bearing, the combination with a housing adapted to be secured to a bolster or the like and having an interior bearing surface; of an anti-friction roller; a rocker pivotally connected to each end of said roller at the axis of the latter so as to be rocked thereby, and having an arcuate bearing surface eccentric to the bearing surface of said roller and projecting therebeyond at the rocker ends, the central portions of said rockers being spaced from said bearing surfaces of the housing when the rockers are in their normal position; and springs at the sides of said rockers for pivotally engaging the same for supporting said rockers together with said roller, said rockers actuating said roller away from the bearing surface of the housing and transmitting the load between said last mentioned bearing surface and the cooperating opposed bolster after the rockers have been rocked a predetermined amount, after which the roller is revolvable about its pivotal connection to the rockers.

4. In an anti-friction bearing, the combination with a bearing surface; of rocking means having arcuate portions adapted to bear upon said bearing surface in certain positions thereof and provided with supporting elements remote from said bearing portions; an antifriction element having a curved bearing surface

adapted to bear on said bearing surface when the parts are centered; connecting means mounted on said supporting elements upon which said anti-friction element is rotatable, 5 said curved bearing surface of said rocking means and said anti-friction element being of different radius whereby the anti-friction element in central position transmits the load in the direction of said bearing surface substantially free of said connecting means and upon 10 movement of the anti-friction element and rocking means to one side of central position, said anti-friction element is supported for rotation about its axis upon said connecting 15 means and transmits the load through said connecting means to said rocking means and said bearing surface; and yieldable means for maintaining said rocking means and said anti-friction element in central position with reference to said bearing surface. 20

5. In an anti-friction bearing, the combination with a bearing surface; of rocking means having arcuate portions in certain positions adapted to bear upon said bearing surface, 25 said rocking means being provided with supporting elements remote from said bearing portions; an anti-friction element having an arcuate bearing surface of lesser radius than the arcuate surface of the rocker means; connecting means mounted on said supporting elements adapted when said rocking means is displaced from its centered position to a predetermined extent to support said roller free of said bearing surface for rotation about its 30 axis, said anti-friction element directly engaging said bearing surface when said rocking means is in central position; and yieldable means for suspending said rocking means and said roller for operative movements, said 35 40 yieldable means co-acting with said rocking means and roller to maintain the same in central position with reference to said bearing surface when free from load.

6. In an anti-friction bearing, the combination with relatively movable members having opposed, parallel bearing surfaces; of a housing secured to one of said members; an anti-friction element engageable by said relatively movable bearing surfaces; movable means 45 50 bearing on one of said opposed parallel surfaces for forcing the anti-friction element away from said surface and supporting the same for rotation about its axis free of said bearing surface when moved beyond a predetermined distance to either side of central 55 position; and yielding means for returning and maintaining said movable means and anti-friction element in centered position with reference to the housing.

60 In witness that I claim the foregoing I have hereunto subscribed my name this 1st day of April, 1924.

JOHN F. O'CONNOR.
